UNITED STATES PATENT OFFICE

149,409

DESIGN FOR A BOOK END OR SIMILAR ARTICLE

Andrew G. Giegold, Jr., Mount Vernon, N. Y.

Application March 2, 1946, Serial No. 127,050

Term of patent 3½ years

(Cl. D33—1)

To all whom it may concern:

Be it known that I, Andrew G. Giegold, Jr., a citizen of the United States, residing at Mount Vernon, in the county of Westchester and State of New York, have invented a new, original, and ornamental Design for a Book End or Similar Article, of which the following is a specification, reference being had to the accompanying drawing, forming part thereof.

Figs. 1 and 2 are perspective views of a book end or similar article, showing my new design.

The dominant features of my design reside in the portions shown by means of full lines in the drawing.

I claim:

The ornamental design for a book end or similar article, as shown and described.

ANDREW G. GIEGOLD, JR.
